(No Model.)

L. W. LESTER.
LOCOMOTIVE BOILER.

No. 479,648.

Patented July 26, 1892.

UNITED STATES PATENT OFFICE.

LEWIS W. LESTER, OF GLENCOE, MINNESOTA.

LOCOMOTIVE-BOILER.

SPECIFICATION forming part of Letters Patent No. 479,648, dated July 26, 1892.

Application filed November 30, 1891. Serial No. 413,544. (No model.)

To all whom it may concern:

Be it known that I, LEWIS W. LESTER, a citizen of the United States, and a resident of Glen-
5 coe, in the county of McLeod and State of Min-
nesota, have invented certain new and useful
Improvements in Locomotive-Boilers; and I
do declare the following to be a full, clear,
and exact description of the invention, such
as will enable others skilled in the art to
10 which it appertains to make and use the
same, reference being had to the accompanying
drawings, and to letters of reference marked
thereon, which form a part of this specification.

15 Figure 1 of the drawings is a representation
of the invention in longitudinal vertical section,
and Fig. 2 is a transverse vertical section.

This invention has relation to certain new
and useful improvements in steam-boilers es-
20 pecially adapted as locomotive-boilers; and it
consists in the novel construction and combi-
nation of parts, as hereinafter specified.

In the accompanying drawings the letter A
designates the fire-box, located under the front
25 portion of the boiler B. Leading from the
fire-box along under the boiler is the external
flue C, opening at its rear end into a smoke
or combustion chamber D at the lower rear
30 portion of the boiler, the top wall of which is
formed by the crown-sheet D' and the front
wall by a half flue-sheet E, carrying the lower
internal flues a, opening into said chamber.
At their front ends these flues open into a
35 smoke or combustion chamber F. Leading
from the upper portion of this chamber are
the flues b in the upper half of the front flue-
sheet. At their rear ends these flues open
40 into a smoke-box G, which extends across the
entire rear of the boiler. Under the lower
portion of the chamber F is the water-space f,
which forms a part of the water-room of the
boiler. In said chamber and secured to the
45 front wall of the boiler is the mud and water
drum H, into the lower portion of which leads
the feed-water pipe g. Communicating with
the central portion of said drum is the pipe
g', leading to and discharging at the center
50 of the boiler.

I is the steam-room, and I' the dome, which
55 are located at the front portion of the boiler.

K is a water chamber or jacket entirely sur-
rounding the fire-box and the flue C and com-

municating with a water-space K' between
the lower portion of the rear flue-sheet k, in
the upper half of which are the flues b, and
the rear wall of the chamber D. Passages k'
are also provided from the waist of the boiler
into said jacket, so that a free circulation of
water is maintained through the whole. This
jacket serves to protect all parts which are
exposed to great heat, and also serves to re-
tain and utilize the heat which would other-
wise escape by radiation from the external
flue, fire-box, and the lower boiler-surface.
The gases of combustion passing from the fire-
box through the flue C not only come in con-
tact with the boiler-surface, but with the wa-
ter-jacket, passing to the chamber D, where
still further combustion takes place, thence
through the flues a to chamber F, thence into
65 the flues b to the smoke-box G and to the
smoke-stack G', thus passing twice through
the waist of the boiler and once externally
thereof, utilizing a maximum per cent. of the
total heat. The feed-water entering the drum
70 H loses a large part of its sediment, becom-
ing heated by the gases in chamber F, which
have free circulation on three sides thereof,
and discharging at the mouth of the pipe g'
in a considerably-heated state, thus effecting
75 a saving of fuel. The upper flues b, passing
through the steam-room, also serve to dry and
superheat the steam.

N is a door for the purpose of removing cinder-
ders from chamber F, and M' the door of the
80 fire-box.

M is a door to the smoke-box G.

The various parts are made secure by stay-
bolts, and longitudinal stay-bars may be em-
ployed wherever necessary. The smoke and
90 combustion chambers, as well as the mud-
drum and water-jacket, are provided with
hand-holes and mud-plugs to facilitate their
cleansing.

It will be observed that the terms "front" 95
and "rear" as herein used are employed in
the manner customary in speaking of boilers
and furnaces wherein the end having the
furnace-door is termed the "front" end and
the opposite end the "rear" end.

Having described this invention, what I
claim as new, and desire to secure by Letters
Patent, is—

1. In a steam-boiler, the combustion-cham-

bers D and F, located at the respective end portions of the boiler, the former being partially inclosed thereby, the external flue C, leading to the chamber D, and the internal flues *a* and *b*, and a smoke-box G, extending along the entire rear of the boiler and into which lead the upper flues, the parts being so arranged that the gases of combustion are caused to pass first from the fire-box externally of the boiler to the chamber D, thence through the flues *a* to the chamber F, and thence through the flues *b* to the smoke-box G, and a mud and heating drum for the feed-water within the chamber F and secured to the front wall thereof, whereby it is subjected on three sides to the gases in said chamber, substantially as specified.

2. A steam-boiler having a combustion-chamber F at its front portion and communicating with the upper and lower flues and a mud and heating drum for the feed-water within said chamber and secured to the front

wall thereof, whereby it is subjected on three sides to the gases in said chamber, substantially as specified.

3. A boiler having a combustion-chamber D at its lower rear portion, into which open the lower flues, a smoke-box G, extending across the entire rear of the boiler and separated from the chamber D at its lower portion by a water-chamber forming a part of the water-jacket, an external flue leading from the fire-box to the chamber D, a second smoke or combustion chamber at the front, into which open both the upper and lower flues, and a mud and heating drum for the feed-water in said chamber and secured to the front wall thereof, substantially as specified.

In testimony whereof I affix my signature in presence of two witnesses.

LEWIS W. LESTER.

Witnesses:

JOHN LINTEN,
F. D. STOCKING.
